UNITED STATES PATENT OFFICE

Application December 3, 1948, Serial No. 63,313

2 Claims. (Cl. 22—90)

2. *Introducing the author*

This invention relates to bottom boards for molds, and more particularly, has reference to a mold bottom board construction including means attached thereto for facilitating the movement of a mold from one location to another.

By way of background, it may be noted that in the handling of molds, it is desirable that the movement thereof from location to location be facilitated. At present, there is not in use so far as I am aware, such a means, and an important object of the present invention is, accordingly, to provide a bottom board construction that will speed up greatly the handling of molds.

It is a purpose, additionally, to provide a means of the character described including a roller mounting for the bottom boards, whereby the molds can be placed upon a mold track or conveyor line, or can be moved out upon the floor, as is often desirable, with speed and ease.

Another important object is to provide a roller mounting for bottom boards which will make possible a very inexpensive mold conveyor line which will find application in small plants as well as in large ones.

Another important object is to provide a roller mounting of the character stated which will have all the advantages of facilitating movement of the molds, but which will not in any way place limitation upon the number and kind of jobs to be handled.

Another important object is to provide a roller mounting for bottom boards which will nevertheless permit mold storage in minimum space, and in such a way that the rollers will not interfere with said storage.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing

Figure 1 is a bottom plan view of a bottom board equipped in accordance with the invention.

Figure 2 is a transverse section through said bottom board.

Figure 3 is an enlarged transverse section through one of the cleats and roller associated therewith.

Figure 4 is a transverse section through a modified form of cleat.

Referring to the drawing in detail, the reference numeral 5 designates generally a bottom board for a mold. In this connection, the present invention does not relate to a special bottom board construction, other than one which will effectively permit the attachment of cleats of the character to be described hereinafter, and rollers carried by the cleats. In this connection, reference may be had to my copending application, Serial Number 613,927, now abandoned, having reference to a bottom board for molds, and such a bottom board is admirably suited for attachment of cleats and rollers. Other forms of bottom boards, however, can as well be used, and it is believed advisable to state only that the boards are preferably of metal material.

Spaced transversely of the bottom board 5 are the parallel cleats 6, these being readily fashioned, in the form of the invention illustrated in Figs. 1 to 3, from channel material. In any event, the web or inner wall of the cleat 6 is fixedly secured in any suitable manner to the under side of the bottom board 5, and extending below the bottom board are the parallel side walls 7, the lower or outer ends of which are formed with the out turned longitudinal flanges 8.

Opposed openings 9 are formed in the side walls 7, receiving the axles 10, which are prevented accidental separation from the cleats by means of the pins 11.

30 means of the pins 11. Mounted for rotation upon the axles 10 are the flanged rollers 12, adapted for rolling upon the tracks T. Tracks T, as will be understood, provide a conveyor line or mold track, so that
35 the molds can be transferred from one location to another with speed and ease. The rollers 12 are preferably ball bearing equipped, and to this end, there is provided adjacent each end of the axle the bushing 13, between which are interposed the spaced apart inner race members 14. Race members 14 are grooved for reception of the anti-friction elements 15, said elements being also received in grooves formed in the outer race members 16 that are secured to the inner
40 surfaces of the outer portions of the rollers. Packing rings 17 are interposed between the race
45 members.

Referring to Fig. 4, a modified cleat construction is there illustrated including the opposed members 18. The longitudinal edges of each member are outwardly flanged as at 19 and 20, and the flanges 19 are secured to the under side of the bottom board 5. The roller carried by the cleat defined by the cooperating spaced apart

members 18 is preferably fashioned in the same manner as the roller of the first form.

It may be noted that the lower ends of the cleats, as defined by the flanges 8 in the first form of the invention and the flanges 20 in the second form of the invention, are disposed lower than the lowermost portions of the rollers 12. As a result, when the mold is removed from the tracks T, it is permitted to rest directly upon the flanges 8 or 20 as the case may be, said flanges defining feet, whereupon the molds are readily adapted for storage, pouring, or other operations. Additionally, it is of importance to note that the side walls of the cleats, and the projecting lower ends of the cleats, protect the rollers completely, and this is of advantage in many operations, as for example, when bottom boards are used on squeezer machines, the pressure will be applied to the cleat side walls rather than to the rollers.

What is claimed is:

1. The combination, with a mold bottom board, of spaced parallel cleats rigidly secured to the under side of the bottom board, said cleats having parallel vertical side walls the lower edges of which are extended outwardly and horizontally to form longitudinal flanges providing feet for supporting the bottom board above a supporting

surface, said side walls and flanges extending the length of the bottom board, and rollers carried by each cleat, the feet projecting below the rollers.

5. 2. The combination, with a mold bottom board, of spaced parallel cleats, said cleats including longitudinal side walls set edgewise relative to said bottom board and extending the length of the bottom board, said side walls being rigidly and permanently secured along their upper edges to the bottom board, rollers carried between the side walls of each cleat, flanges on the lower ends of the side walls and extended horizontally and outwardly from the side walls, said flanges projecting beyond the lowermost points of the rollers, and said rollers being flanged for track engagement.

C EDWARD WESTOVER.
